UNITED STATES PATENT OFFICE.

GEORGE BURDICK, OF CLEVELAND, OHIO, ASSIGNOR TO THE CHAMBERLIN
CARTRIDGE COMPANY, OF SAME PLACE.

CARTRIDGE-LOADING MACHINE.

SPECIFICATION forming part of Letters Patent No. 357,457, dated February 8, 1887.

Application filed May 20, 1886. Serial No. 202,763. (No model.)

To all whom it may concern:

Be it known that I, GEORGE BURDICK, a citizen of the United States, residing at Cleveland, in the county of Cuyahoga and State of Ohio, have invented new and useful Improvements in Cartridge-Loading Machines, of which the following is a specification.

This invention relates to an improvement in cartridge-loading machines described in United States Letters Patent No. 295,980, granted to Franklin L. Chamberlin; and it consists in certain novel features of construction, which are fully pointed out in the following specification and claims, and illustrated in the accompanying drawings, in which—

Figure 1 represents a front view of my machine. Fig. 2 is a horizontal section in the plane $x\ x$, Fig. 1. Fig. 3 is a similar section in the plane $y\ y$, Fig. 1. Fig. 4 is a horizontal section in the plane $z\ z$, Fig. 1, looking upward. Figs. 5, 7, and 8 are detail views of the shell-crimping device. Fig. 6 is a sectional view of a wad-feeding tube. Fig. 9 is a detail view of the wad-pusher mechanism.

Similar letters indicate corresponding parts. In the drawings, the letter A designates a column which supports the platform B, and in which is firmly secured the vertical spindle C.

D is the shell-carrier, which rests upon the platform B and turns loosely upon the spindle C. A step-by-step movement is imparted to the carrier by any mechanism suitable for this purpose—such, for instance, as a dog, a, which extends from the main shaft E, Fig. 1, and which engages with a series of cavities or recesses, b, Fig. 4, in the bottom surface of the carrier. After each forward movement the carrier is locked by a stop-pawl, c, Figs. 1 and 4, which engages with one of the holes e, and which is thrown out of such hole by a cam, f, Fig. 1, which is mounted on the main shaft and acts upon a lever, g, just before the next forward movement of the carrier is to take place. The lever g can be depressed by hand so as to release the carrier whenever it is desirable. In the circumference of the carrier are a series of semicircular recesses, h, which correspond in number and position to the

number and position of the propelling cavi-

ties b. In the example shown in the drawings nine such cavities are shown, so that for each revolution of the main shaft the carrier is turned one-ninth of a whole revolution. Each of the semicircular recesses h in the carrier is provided with a semicircular door, i, which swings on a vertical pivot, j, Figs. 1, 2, and 3, and which is provided with a pin, k, Figs. 1 and 3, projecting beneath its bottom edge. The door is normally retained in a closed position by a spiral spring, l, wound round its pivot, (see Fig. 1;) but as the carrier revolves the pin k of each door engages with a stationary cam, m, (see Figs. 1, 2, and 3,) which is firmly fastened to the platform B in close proximity to the tube F, through which the cartridge-shells are fed to the machine. A cartridge-shell dropped into this tube rests upon the platform B in a vertical position, and as the carrier D revolves in the direction of the arrow shown near it in Fig. 3 the door i next to the tube F is gradually opened by the cam m, so that it passes in front of the shell situated in the tube F, and when the pin k of the door has passed the cam m the door closes and forces the shell into the recess h of the carrier. The motion of the carrier is so timed that the carrier remains stationary in the position shown in Fig. 3, the door i of the recess h being partially open.

On the next forward movement of the carrier the recess h is moved beyond the tube F, and during this movement the door i closes upon the shell in the tube, and as the motion of the carrier continues the movable section f^m of the tube F is forced open against the action of its spring and the shell is carried to the position indicated by the letter, S, in Fig. 3, and hereinafter designated as the "first station." Immediately after the shell has passed out of the tube F the movable section of this tube closes, leaving the tube in the proper condition for the reception of the next shell.

As the shell contained in the tube F is carried out of this tube to the first station, S, Fig. 3, its rim acts upon a lever, n, which is firmly mounted on a vertical spindle, o. This lever acts on the powder-container J, so that the operation of the machine will cause the desired

quantity of powder to be deposited in the shell when it is at that station. The shot is deposited into the shell in a similar manner at another station; but these do not form any part of my 5 present invention.

As the shell is being carried from the first to the second station its rim acts upon the lever O, which is mounted upon a vertical spindle, o'. This spindle has its bearing below in a 10 socket in the platform B and above in an arm, P, which extends from the hub I, Figs. 1 and 3. On the spindle o', near its upper end, is firmly mounted a lever, o'', with a curved slot, o''', which engages with a pin, o'', Figs. 3 and 4. 15 This pin projects from a carriage, p', which moves in a radial slot in the arm P, and which carries the wad-pusher p''.

To facilitate the proper adjustment of the levers O and o'', both of which are firmly secured 20 to the vertical spindle o', this spindle is made in two sections, m' and m'', Fig. 9, which are connected to each other by a sleeve, m'', which carries a set-screw, m''. By this means I am enabled to adjust the relative position of 25 the levers O and o'' with ease, either when first assembling the parts or when they have been worn from use.

The wad-container Q consists of a series of 30 vertical rods, or of a tube, and it is provided with a gate, q', which can be adjusted so that the lowest wad in the wad-container can be pushed out by the pusher p''. As the rim of the shell passes the lever O the pusher p'' is forced inward by the slotted lever o'', and the 35 lowest wad is carried over the shell, where it is retained by two spring-jaws, q'', Fig. 2. The pusher p'' is immediately drawn back by the action of the rim of the shell upon the nose o''' of the lever O, Fig. 3, whereby the spindle o' 40 is turned back to its normal position. The shell has now reached station S', right beneath the wad, and the wad is driven down into the shell by the rammer R.

As it is desirable that the wad-container Q, 45 which, as above described, may either consist of a tube or a series of vertical rods, should contain as large a number of wads as possible, it is made of the greatest possible length which the practical construction of the machine will 50 permit, and which is approximately indicated in Fig. 1 of the drawings; but the length of the wad-container there shown will hold only comparatively few wads—say one hundred—and would have to be refilled continuously 55 by the operator. To obviate this constant filling by the operator, I employ removable wad-feeding tubes K, Figs. 1 and 6, which contain a large number of wads. These tubes may be filled either directly at the wad-cutting 60 machine or by a much cheaper grade of labor than that employed to run my machines, permitting one operator to run three cartridge-loading machines with ease, where one such machine formerly demanded his whole time. 65 These wad-feeding tubes may be perfect tubes with an opening at or near the lower end, or they may have a slit running their whole

length, so as to permit the operator to notice the number of wads in the tube at any time and to remove the tubes when the wads therein 70 have reached a point when it is necessary to insert a full feed-tube. To insure the downward passage of the wads in these tubes, I employ a weight, O'', which will keep them in proper position and prevent the clogging of 75 the tube.

By the subsequent movements of the carrier D the shell is moved successively to the stations S² S³, in each of which it receives an additional wad. Then it is moved to the station S⁴, in which it receives the shot, which is introduced into the shell from the shot-container J' precisely in the same manner in which the powder is introduced from the powder-container J. After the shell has been charged 85

with shot it is moved by the carrier to the station S⁵, in which it receives a wad, and then it is moved to station S⁶, in which it is crimped. This operation consists in turning over the upper edge of the shell after it has 90 been loaded, as seen in Fig. 8, and is effected by means of the rotary crimpler T, the form of which is shown in Figs. 7 and 8. This crimpler consists of a thimble, p, in the under surface of which is formed an annular 95 groove, q, the bottom of which is rounded. Into this thimble are inserted the crimping-pins p'', into each of which is cut a groove, p''. These pins extend into the annular groove q in such a way that while the grooves p'' 100 in the pins register with the annular groove q the bottom of each groove p'' in the pin is situated in a different plane from the bottom of the annular groove q in the thimble, thereby forming concave projections, Fig. 8, 105 which act on the edge of the shell and turn the same down, while the sides of this annular groove embrace the shell and prevent its distortion during the crimping operation. It is evident that the same result might be obtained 110

by forming the concave projections p'' directly on the bottom of the annular groove in the thimble. The difficulty of construction of such a form of crimpler is obvious, while by means of the crimping-pins the concave projections p'' can be produced without difficulty. These radial crimping-pins are adjustably 115 fitted in the thimble, so that they can be rotated axially in their seats for the purpose of bringing new or fresh portions of their annular grooves into position for crimping when such grooves become worn in one place. The pins are also readily removable, so that they 120 can be replaced by new ones, when desired, at small expense.

In the example shown in the drawings, Fig. 1, the crimpler is secured to a spindle, t', which slides loosely through a bearing, t'', in an arm, U, extending from the hub I, and also through the cross-head N, and is provided with an adjustable collar, t''. At its upper end is formed a conical teat, which fits a socket in the vertical shaft t', which has a sliding bearing in the journal-box M, and which carries the pulley 125 130

t^6 , connected by a belt with a counter-shaft, as shown in Fig. 1, from which the required rotary motion is imparted to the shaft t^4 and to the spindle t' carrying the crimper T. In addition to a rotary motion, the crimper must also have a rising and falling motion, so as to release the shell after it has been crimped. This is accomplished by the cross-head N, to which a rising and falling motion is imparted from the main shaft E. In this cross-head is formed the bearing t^6 for the spindle t' , and in the example shown in the drawings, it consists of a bushing held in position by a nut. When the cross-head is down, the crimper will rest on the shell by the weight of the parts to which it is connected, in which position it will remain until it has performed its function, when its further downward motion will be arrested by either or both of the collars t^7 t^8 . As the cross-head rises it will strike the collar t^2 on the spindle t' , and carry the spindle and the parts connected to it upward and out of action until a new shell shall have come under the crimper, when it again descends, thereby permitting the crimper to act on said new shell. To prevent noise and to take up the shock of the cross-head against the collar t^2 , a coiled spring, t^9 , is placed between these parts.

I am aware that a shell-crimper has been heretofore composed of a cup-shaped bit having a circular groove in its base and provided with radial pins extended across said groove, slightly raised, and having inclined grooves across their upper sides to assist in turning the edges of the shells inward. Such, therefore, I do not claim.

What I claim as new, and desire to secure by Letters Patent, is—

1. The combination, in a cartridge-loading machine, of the upright column A, the platform B thereupon, the shell-carrier D, resting on the platform, and means for intermittently rotating said carrier, with the vertical rotating shaft carrying a shell-crimper, T, at one end, and an automatically rising and falling cross-head, N, having a bearing, t^6 , through which the crimper-carrying shaft passes, substantially as described.

2. The combination, in a cartridge-loading machine, of the upright column A, the platform B thereupon, the shell-carrier D, the main shaft E, connections between the main shaft and the carrier for rotating the latter, the vertical rotating shaft carrying a shell-crimper, T, and a cross-head, N, connected with the 55 crimping-carrying shaft and raised and lowered by the main shaft, substantially as described.

3. The combination, with the shell-carrier D and driving-shaft E, of a rotating shaft carrying at one end a shell-crimper, T, and a yoke, 60 N, connected with and raised and lowered by the driving-shaft, and mounted on the crimping-carrying shaft for moving it lengthwise, substantially as described.

4. A crimper for cartridge-shells, consisting 65 of a thimble having an annular groove, g , and radial pins p^6 , provided with annular grooves q , extending across the groove in the thimble and adjustably fitted thereinto to rotate axially for bringing new parts of the grooves in the 70 pins into position for crimping, substantially as described.

5. The combination, with the shell-carrier D and driving-shaft E, of a shaft having the pulley t^6 , for rotating it, and provided with the 75 shell-crimper T, the stationary bearings M and t^{10} , the collar t^2 , and a cross-head, N, connected with the driving-shaft and mounted on the crimping-carrying shaft, for moving it lengthwise in its bearings, substantially as described. 80

6. The combination, with the shell-carrier D, lower and upper levers, $O o^2$, arm P, and the carriage p' thereupon, connecting with the upper lever and carrying the wad-pusher, of a spindle, o' , composed of two sections, $m m'$, 85 adjustably coupled together, and to which sections the levers are respectively secured, substantially as and for the purpose described.

In testimony whereof I have hereunto set my hand and seal in the presence of two subscribing witnesses.

GEORGE BURDICK. [L. S.]
